A. F. BROWN.
METALLIC RAILWAY TIE.
APPLICATION FILED MAY 26, 1920.

1,373,947.

Patented Apr. 5, 1921.

Augustus Freedorn Brown

By J. Walter Fowler

Attorney

UNITED STATES PATENT OFFICE.

AUGUSTUS F. BROWN, OF HAVRE DE GRACE, MARYLAND.

METALLIC RAILWAY-TIE.

1,373,947.

Specification of Letters Patent.

Patented Apr. 5, 1921.

Application filed May 26, 1920. Serial No. 384,394.

To all whom it may concern:

Be it known that I, AUGUSTUS F. BROWN, a citizen of the United States, residing at Havre de Grace, in the county of Harford 5 and State of Maryland, have invented certain new and useful Improvements in Metallic Railway-Ties, of which the following is a specification.

My invention relates to certain new and 10 useful improvements in metallic railway ties, and to the particular type of such ties which is identified with or designed for use on lines of railways employing electricity for motive power, signaling, etc., and where- 15 in the tie is insulated against the short-circuiting of the electric current.

A leading object of the present invention is to devise a metallic tie of a sectional character wherein the assembled sections or 20 parts of the tie may be fully insulated from each other and may be united, by bolts or equivalent fastenings so as to make the tie rigid and the sections or parts thereof substantially immovable relatively to each 25 other, either vertically or horizontally.

A further object of my invention is to so 30 fashion the opposed faces of the sections or parts of the divided tie that a strong and substantial interlock is produced to thereby resist movement, vertically or horizontally, 35 of one section or part relatively to the other, the interlocking faces of said sections being provided with an appropriate insulating material and the uniting bolt being, also, insulated 40 so as to maintain an efficient guard against the short-circuiting of the electric current in lines of railway employing a third rail, or other means for conducting an electric current to the usual motor of the 45 car, locomotive or other vehicle, or for signaling, etc.

Another object of the present invention is 50 to provide a simple and efficient means for preventing the accumulation of cinders on the top of the tie and the short-circuiting of the electric current by reason of the cinders extending substantially across the tie and thereby forming a conductor of the electric circuit from one side rail to the other.

With the above and other objects in view, 55 my invention consists of the parts and the constructions, arrangements and combina-

tions of parts which I will hereinafter describe and claim.

In the accompanying drawing forming 55 part of this specification, and in which similar reference characters indicate like parts in the several views;—

Figure 1 is a side elevation of a metallic railway tie, embodying my invention. 60

Fig. 2 is a top plan view of the same.

Fig. 3 is a horizontal section on the line 3—3 of Fig. 1.

Fig. 4 is a face view of a fragment of the tie showing the connecting ends of the tie 65 separated.

In carrying out my invention I may construct the tie of suitable metal and of any desired design, and said tie will be fashioned or provided with appropriate end seats, A, 70 for the placing of the usual track-rails and of such rail fastening devices as may be deemed best for the particular purposes for which the tie is intended. In this connection the tie illustrated in the present drawing may represent or be considered as embodiments of the ties and rail fastening features of my former Patents Nos. 1,127,350, February 2, 1915; 1,158,975, November 2, 1915; and 1,253,779, January 15, 1918, but 75 it will be understood that the present improvements which are restricted to the construction of the tie proper, may be used in connection with other designs of ties and associated with different means for securing 80 the rails thereto.

Instead of the single-piece tie of some of my former patents, I now divide the tie at a point between ends, thus making the present tie of the general character of the one shown, 90 described and claimed in my former Patent Number 1,309,455, dated July 8, 1919, and on which latter tie the present invention is an improvement; some of the present novel features may, however, be readily used in 95 connection with the specific joint of the said patent, as I will hereinafter show.

One of the leading features of improvement relates to the provision of means for preventing such a lodgment of cinders on 100 the tie as to form a conductor and result in the short circuiting of the current in electrically installed railways. It is generally known to electrical engineers, that in the or-

dinary relatively straight flat-top ties which are usually ballasted on cinders, that particles of the cinders often accumulate thereon, from various causes, such as passing trains, to such an extent that they extend continuously, either in straight or irregular lines or paths, from one rail to the other. These cinders are, as a matter of fact reasonably good conductors of electricity, and when 10 the accumulation is such as to form substantially a line of cinders between the rails, they will short-circuit the current, thereby impairing the efficiency of the system and making it difficult to locate and remove the 15 trouble.

A further objection to the existing ties and particularly to those of the divided type employing insulation in the joint between the sections of the tie, is that the tie 20 usually rests directly on the ballast at its jointed center as well as at the ends, and if the jointed portion of the tie should rest upon a bed containing a considerable amount of moisture, the moisture will first attack 25 the metal sections of the tie and produce a rust which, experience shows, will in time enter the joint and attack the interposed fibrous insulating material and finally cause the same to disintegrate thereby destroying 30 its intended function. To meet both of the foregoing serious objections, I construct the present tie, A, with an arched central portion, A', which when the tie is in place, is sufficiently raised above the ballast to prevent 35 moisture in or on the latter creeping into the joint of the divided tie, in which arched central portion of the tie the insulated joint is usually formed. In other words, I do not essentially disturb the arrangement of the ends of the tie with its 40 rail seats and accessories, and the under sides of which rest solidly upon the road ballast, but I arch or elevate a substantial portion of the middle part of the tie, as indicated in Fig. 1.

In this arched portion the joint of the sectional tie is formed, said joint being insulated to prevent electric current passing from one section of the tie to the other. In 50 connection with the arching feature, I may use the joint of my said prior Patent Number 1,309,455, or I may use any desired design of joint, including the one I will hereinafter describe.

55 The arching of the central portion of the tie not only maintains the joint against the injurious influence of moisture in the road bed, but it also makes the top of the tie substantially discontinuous and therefore 60 cinders cannot accumulate in an unbroken layer thereon to afford means for short-circuiting the current, as the curved surfaces produced by the arching afford no resting place for cinders and at most only 65 a broken line of cinders could occur and

such broken line would effectively prevent the current being shortcircuited thereby.

In the present case as in the aforesaid prior patented construction Number 1,309,455, the tie is divided vertically into sections A, A' to form two matching portions, each provided with ribs and recesses, of which there may be any desired number, the arrangement being such that when the two sections are fitted together, the meeting faces are brought into close engagement with an intervening insulating material, and shoulders are formed which by their intimate engagement prevent the assembled sections from having relative movement in any direction. Specifically, I alter the form of the rib-and-recess or interlocking joint in the present instance and instead of dividing the tie along truly horizontal and vertical lines and employing vertical shoulders and recesses, I construct the joint substantially as follows:

The meeting faces of the sections of the tie I recess for about one-half their thickness so that when the sections are fitted together the outer faces of the sections at the joint will be flush with the remaining portions of the outer sides. One end of each section I form at an incline, as shown at 10, and the wall of this inclined portion I bevel outwardly, as at 12. Each section of the tie is further formed with an under-cut inclined shoulder, 13, at the base of the recess formed by halving the meeting face of the section, the inclination of this shoulder, being substantially opposite to the incline, 10, given the extreme end of the section whereby the recess which is formed in the inner face of each section has the general shape of a flattened "Z" and the inclined beveled end of one section will conform to and closely fit into the inclined under-cut shoulder 13 of the other section and the sections will become intimately locked and can only be separated by sliding one section on the other in a plane which is substantially parallel to the inclined surfaces 10, 13. The sections cannot, therefore, be separated longitudinally or vertically nor can they be fitted together except by the inclined edgewise sliding action of one section on the other, as before noted.

In addition to the recessing of the meeting faces of the sections, I supply one of said faces with a rib, 14, which is arranged at an incline corresponding to that of the under-cut shoulder of said section; the meeting face of the other section of the tie, I form with an inclined recess, 15, which is parallel with the inclined end of said section and is so fashioned that it will slidably receive the aforesaid rib 14. The result of this construction is, that when the sections are fitted together the inclined end of one section will fit within the undercut recess of the other 130

section and the inclined rib 14 of one section will fit the corresponding recess, 15, of the other section. Both sections are then united and made secure by a bolt, 16, or other fastening.

Between the meeting faces of the sections and closely conforming to the configuration given the same including the undercut shoulders, I place a piece or sheet 17 of suitable material for electrically insulating the joint, and in order to more effectively guard against a possible short-circuit of the current on lines employing my tie and where electric current is used for motive power, signaling, etc., I likewise insulate the bolt, 16, by a sleeve or tube, 18, of appropriate material, as in my aforesaid prior Patent Number 1,309,455.

By reason of the foregoing construction, I am enabled to construct a tie of a sectional character and wherein the sections when once made may be quickly assembled to form the complete tie, and where complete insulating of the tie may be effected and where the insulation is protected and serves as an effective guard against the entrance of moisture between the contacting faces of the sections, and where all tendency of the sections to separate either horizontally or vertically will be resisted by the inclined shoulders formed on the respective sections, thereby relieving the bolt of the shearing strains which would otherwise be brought upon it.

What I claim as my invention and desire to secure by Letters Patent is:—

1. A metallic railway tie composed of substantially similar sections having overlapping portions with interlocking faces, and means between said faces for insulating one section of the tie from another, said tie being arched in its intermediate portion so as to elevate the bottom of the interlocked insulated portion a substantial distance above the road-bed.

2. A sectional metallic tie having similar end portions and a divided intermediate portion the under surface of which is arched to elevate the same above the corresponding under surfaces of the ends and for a substantial distance above the road-bed.

3. A metallic railway tie composed of substantially similar sections having overlapping portions provided with interlocking insulated faces, said tie having a portion of its upper surface longitudinally curved to prevent the accumulation of a short circuiting deposit of particles thereon.

4. A metallic railway tie composed of substantially similar sections having overlapping portions provided with interlocking insulated faces, said tie having its upper surface discontinuous and substantially undulating to prevent the accumulation of a short circuiting deposit of particles thereon.

5. A metallic railway tie composed of sub-

stantially similar sections and having overlapping portions intermediate of its ends, said portions provided with interlocking insulated faces, and the upper portion of the tie being discontinuous to prevent the formation of an unbroken line of particles deposited thereon.

6. A metallic railway tie composed of substantially similar sections having overlapping portions at their inner ends, each of said portions being recessed to form matching faces, each section of the tie having its inner end inclined and transversely beveled, and having an oppositely inclined undercut shoulder conforming to and adapted to receive and interlock with the inclined end of the opposing section, one of said meeting faces having an inclined recess substantially parallel with the inclined end of the said section, and the face of the opposing section having an inclined rib to slidably engage said recess.

7. A metallic railway tie composed of substantially similar sections having overlapping portions at their inner ends, each of said portions being recessed to form matching faces, each section of the tie having its inner end inclined and transversely beveled, and having an oppositely inclined undercut shoulder conforming to and adapted to receive and interlock with the inclined end of the opposing section, one of said meeting faces having an inclined recess substantially parallel with the inclined end of said section, and the face of the opposing section having an inclined rib to slidably engage said recess, and an insulating material between the faces of the sections and the inclined shoulders and rib and recess and insulating one overlapping portion of the tie from the other.

8. A metallic railway tie composed of substantially similar sections having overlapping portions at their inner ends, each of said portions being recessed to form matching faces, each section of the tie having its inner end inclined and transversely beveled, and having an oppositely inclined undercut shoulder conforming to and adapted to receive and interlock with the inclined end of the opposing section, one of said meeting faces having an inclined recess substantially parallel with the inclined end of said section, and the face of the opposing section having an inclined rib to slidably engage said recess, an insulating material between the faces of the sections and the inclined shoulders and rib and recess and insulating one overlapping portion of the tie from the other, and an insulating fastening passing transversely through said sections.

9. A metallic railway tie composed of substantially similar sections having halved inner ends forming recessed faces with oppositely inclined portions, one of said inclined

portions being transversely beveled and the other portion being likewise beveled to form an undercut shoulder, said sections adapted to be fitted together by an upwardly inclined movement of one section relatively to the other, one of said sections having an inclined recess in its face and the other sec-

tion having a correspondingly inclined lug to slidably engage the same, means for insulating the adjoining faces of the sections, 10 and means for fastening the divided portions of the sections together.

In testimony whereof I affix my signature.

AUGUSTUS F. BROWN.
